UNITED STATES PATENT OFFICE.

POWELL EVANS, OF PHILADELPHIA, PENNSYLVANIA, ASSIGNOR, BY MESNE ASSIGNMENTS, TO GLOBE AUTOMATIC SPRINKLER COMPANY, OF PHILADELPHIA, PENNSYLVANIA, A CORPORATION OF PENNSYLVANIA.

DRY-PIPE VALVE.

1,226,489.

Specification of Letters Patent.

Patented May 15, 1917.

Application filed December 17, 1914. Serial No. 877,785.

To all whom it may concern:

Be it known that I, POWELL EVANS, a citizen of the United States, residing in Philadelphia, Pennsylvania, have invented certain Improvements in Dry-Pipe Valves, of which the following is a specification.

One object of my invention is to provide a dry pipe valve which shall be substantial in construction and of such design that its operation will be certain even after the lapse of long periods of time, the invention also contemplating the provision of means for adjusting the position of the water valve or clapper relatively to its seat for the purpose of taking up any slack or lost motion between certain of the elements and their associated parts as well as to prevent leakage.

Another object of the invention is to provide a novel arrangement of valves, connections and weight for controlling the operation of the water valve of a dry pipe system, the construction being such that the weight is wholly outside of the valve casing and is provided with novel means for connecting it to the water and air controlling valves.

The invention further contemplates novel means for preventing accidental closure of the main water and air valves due to rebounding after they have once been opened and also includes means for holding the main air valve in its open position in order that an attendant shall be compelled to open the valve casing and inspect the mechanism before said valve can be returned to its seat.

These objects and other advantageous ends I secure as hereinafter set forth, reference being had to the accompanying drawings in which:

40 Figs. 1 and 2 are vertical sections illustrating a dry pipe valve constructed according to my invention, with its parts in the positions occupied before and after operation respectively.

45 Fig. 3 is a plan partly in section illustrating the form and disposition of parts within the lower part of the valve casing, and

50 Fig. 4 is a fragmentary vertical section illustrating a modified form of one of the parts of the valve mechanism.

In the above drawings 1 represents a casting forming a valve casing divided into two chambers by a partition 2 in which is an

opening having a valve seat 3 for the main air valve or clapper 4. The lower of the two chambers 5 thus formed has in its lower part an inlet opening provided with a valve seat 6 for the reception of the main water valve or clapper 7 which is connected to an arm 8 pivoted to the casing structure by a pin 9. This connection between the arm and the valve is such as to permit of slight universal movement of said valve upon the arm and consists of an integral threaded projection 10 extending from the valve through the arm 8, with a retaining nut 11.

The upper chamber 12 has an overhanging side portion formed with an opening in which is a valve seat 13 for the reception of an auxiliary air valve 14 and similarly there is an opening having a seat 15 in the adjacent side wall of the lower chamber 5. This latter seat preferably lies in a plane substantially at right angles to the plane of the seat 13 and is designed for the reception of a valve 16 within said lower chamber. Said valve is pivoted upon a lever 17 which has, stops 18 placed to limit its pivotal movement and said lever is pivoted or hinged by a pin 19 to an arm 20 hinged to the casing structure by the pin or spindle 9 on which the arm 8 is pivoted. This arm 20 projects forwardly beyond the pin 19, having movably connected to its free end a short bolt 21 which extends through an opening in the valve casing 1 and has threaded upon its outer end a flanged cap 22. The flange of this cap lies within an enlargement of the opening through which the bolt passes, where it is held in any given position by a flanged jam nut 23. The outer end of the adjusting cap 22 is suitably formed for the reception of a wrench and the arrangement is such that by turning it the lever arm 20 is swung upon the spindle 9 as a fulcrum, thereby altering the relative positions of the pivot pin 19 and the valve arm 8 and hence the position of the valve 7 relatively to its seat. After adjustment, the cap 22 is locked in any given position by means of the nut 23 and with it prevents leakage from the valve casing.

The lever 17 has rotatably mounted upon it a tumbler 24 formed with a notch for the reception of the suitably formed end 25 of the valve-carrying arm 8 which is designed

to engage it at a point to one side of a line connecting the centers of the pin 19 and of the pin 26 whereby the tumbler is hinged or pivoted to the lever 17. Rotation of this 5 tumbler in a clockwise direction is limited by the web 17^a connecting the side elements of this lever.

The valve 16 is connected by a link 27 to a lever 28 hinged by a pin 29 to suitably 10 formed lugs integral with the casing structure adjacent the valve seat 15. This link passes through the opening in said seat and is connected to the lever 28 by a pin or spindle 30 on which is also pivotally mounted a weight 31 having a projection 32 designed to engage one arm of a lever 33 fulcrumed on a pin 34 carried by a lug 35 extending downwardly from the under face of the valve 14. A second arm of this lever 20 33 is designed to bear upon a lug 36 projecting from the inner surface of the valve seat 13 so that when the parts are in their set positions the pressure of the projection 32 of the weight upon the lever 33 tends 25 to push the valve 14 upwardly. This valve is fixed to an arm 37 pivoted or hinged to the casing structure by a pin or spindle 38 which also serves as a pivot for the main air valve 4.

30 Connecting with the opening in which is mounted the valve seat 6 is a flanged inlet 39 designed to be connected to a source of water under pressure and a flanged outlet 40 is provided at the top of the air chamber 35 12, it being understood that openings having suitable doors, indicated in dotted lines in Figs. 2 and 4, are provided in the walls of the chambers 5 and 12 for the purpose of assembling, inspecting and setting 40 the various parts.

The auxiliary air valve 14 has a pair of lugs 41 projecting from its top face and providing bearings for a spindle 42 on which is mounted a catch in the form of a 45 lever 43. The top of the main air valve 4 is formed with a projecting web 44 having an overhanging edge 45 so proportioned that when said valve swings through an angle somewhat less than 180°, it engages 50 one arm of the lever 43, turning it on its pivot pin and finally passing it, so that the projecting end 46 of the web rests upon a ledge 47 of the valve casing. By this means the valve 4 is temporarily locked or connected to the valve 14, for the short arm of the lever 43 engages the inner part of the overhanging edge 45 when the main valve is moved from the position shown in Fig. 2, so that it is necessary in order to 60 couple said valves, that the lever 43 be swung or allowed to swing on its pivot until it is clear of said overhanging edge.

The web 44 of the valve 4 has one or 65 more openings 48, for the purpose of permitting mud or other foreign material to

wash out, and it is noted that the construction is designed to require an inspection of the valve 14 and its seat whenever the main valve is moved from its open to its closed position by an operator, such inspection being necessarily incidental to the uncoupling of the valves. In order to insure that the water valve 7 will not rebound from its stop 49 when violently opened by the flow of water through the apparatus, I provide a 75 lever 50 so pivoted within the chamber 5, that while it may be turned on its pivot in one direction when engaged by the nose 25 on the valve supporting arm 8, when the valve moves toward its fully open position, 80 said lever will not move in the opposite direction but is held by reason of its engagement with a part of the casing. This retains the lever in such position that before the valve 7 with its arm 8 can be moved 85 from the position shown in Fig. 2, to that shown in Fig. 1, said lever must be manually turned into such a position that its lower arm will permit passage of the nose 25.

90 Similarly I pivot adjacent the valve 4 an arm 51 which while normally resting against its side at a point opposite the pivot 38, will fall under it as it opens and will effectually prevent it from dropping back 95 into its closed position. The weight 31 and its associated parts outside of the casing structure are inclosed by a suitably formed cover 68 hinged to the main casing structure by a spindle 69.

100 Under conditions of use the main air and water valves 4 and 7 are placed upon their seats, the valve 4 being first uncoupled from the valve 14 and the levers 50 and 51 being manipulated to permit of their passage 105 from their open positions. The auxiliary air valve 14 being likewise seated, air is admitted to the chamber 12 under the pressure which it is desired to maintain in the sprinkler system connected to the outlet 40. 110 The weight 31 is then raised to the position shown in the drawing, thus causing its lug 32 to pass under the downwardly projecting arm of the lever 33, and moving the valve 16 with its arm 17 inwardly from the valve seat 15. This inward movement of the said members causes the projection 25 on the valve-carrying arm 8 to enter its notch in the tumbler 24, after which the weight 31 may be released, when the air pressure on the valve 14 holds it with its associated parts in the set positions shown. If necessary the jam nut 23 is slackened off and the cap 22 adjusted so that the valve 7 is held tightly to the seat 6, after which water 115 under pressure may be admitted to the inlet 39 and the system is ready for operation.

120 If at any time the air pressure in the chamber 12 falls below a predetermined point, as it would upon the operation of one 130

or more sprinkler heads, the valve 14 is forced upwardly by the pressure exerted by the water through the valve 7, arm 8, tumbler 24, arm 17, valve 16, link 27, arm 28, spindle 30, abutment 32, and lever 33, and partly by the weight 31 whose action is transmitted through the abutment 32 and lever 33 to said valve. When this latter, by reason of the reduction of pressure in the chamber 12, rises sufficiently to permit the abutment 32 to clear the lower end of the lever 33, the weight 31 swings down on its pivot 30 and coming in contact with a portion of the arm 28, turns this latter on its hinge or pivot 29. The valve 16 is thereby caused or assisted to move into engagement with its seat 15 and the lever 17 moves the tumbler 24 out of engagement with the end 25 of the arm 8 so that the valve 7 is free to swing on its pivot 9 past the lever 50 which turns on its pivot spindle and into a fully open position at one side of the valve casing 1, out of the line of the inlet and outlet. As previously noted said lever 25 effectually prevents any rebound of the valve to its closed position so that water from the inlet 39 enters the chamber 5 which it quickly fills and thereafter acts on the valve 4 so as to swing this back on its pivot or hinge 38. In so moving it lifts the arm 51 and then drops it, thereafter turning until the edge 45 of its web engages and passes the lever 43 of the valve 14.

After the upward movement of the valve 14 releases the weight 31, said valve falls back upon its seat 13 and as above noted, the valve 4 shortly thereafter moves into a position immediately over it, out of the line of the water current, which passes out of the chamber 12 through the outlet 40. It will be noted that the weight 31 not only gives positive assurance of the opening of the valve 14 but also acts through the link 27 to positively swing the arm 17 with its tumbler 24 away from the valve carrying arm 8, it being obvious that the valve 16 seats upon its ring 15 so as to effectually prevent escape of water from the chamber 5.

In that form of my invention shown in Fig. 4 I have illustrated another arrangement of parts whereby the water valve may be adjusted relatively to its seat and for this purpose I pivot the valve-carrying arm 8 by a pin 62 to one end of a lever 60 whose opposite end is pivoted or fulcrumed by a pin 61 to the valve casing. At a suitable point intermediate its ends I connect to said lever 60 the bolt 21 which as before, extends through the valve casing 1^a and has threaded on its outer end a cap 22^a which may be clamped in any adjusted position by a flanged nut 23^a. In this case the lever 17^a is pivoted on a rod or pin 19^a whose ends 65 are carried in the walls of the valve casing

and said lever carries a rotatable tumbler 24 placed to be engaged by the nose or end of the valve-carrying arm 8.

In this case the weight 31^a is carried on an arm 63 extending into the valve casing 70 and pivoted by a pin 30^a to the upper end of the lever 17^a, adjacent which it has the form of a valve 16^a designed to engage a seat 15^a mounted in the opening in the valve casing. Adjacent the valve 16^a this 75 arm 63 has a hooked finger 32^a designed to coact with a lever 33^a pivoted to a pair of lugs on the under side of the controlling or auxiliary valve 14^a which is prevented from rising more than a predetermined distance from its seat by a hook 64 connected to it by the same pin 34^a as that which attaches the lever 33^a.

When the parts of the valve are in their set positions this hook 64 rests upon a pin 85 66 carried by a lug or pair of lugs 67 projecting into the chamber 5^a of the casing, but as soon as the controlling valve 14^a has risen a predetermined distance from its seat, said hook falls into positive engagement with the pin 66 thereby preventing further rise of the said valve. As before, adjustment of the cap 22^a raises or lowers the bolt 21 and this, by moving the lever 60 on its pivot, adjusts the water valve 7^a 95 relatively to its seat.

It is to be particularly noted that the various parts of my valve have been designed and arranged in order that the device shall not be likely to get out of order 100 or have its elements easily disarranged even by rough handling. The resetting of the valve may be accomplished with ease and certainty while the outlines of the members are such as to render difficult, if not impossible the wedging or blocking to which apparatus of this class is frequently subjected. Moreover the construction is such that there is but little likelihood of the valve getting out of order or failing to 110 properly perform its required functions even after the lapse of long periods of time.

In resetting the apparatus it is necessary to manually hold the lever 43 while the main and auxiliary air valves are separated and in so doing the operator is necessarily led to inspect the valve seats, so that the possibility of pieces of solid material being allowed to remain on said seats is reduced to a minimum. The necessity for turning the 120 two levers 50 and 51 in resetting the water and main air valves also requires such attention from the operator that all parts of the mechanism are inspected before the apparatus is again ready to be connected to the air 125 and water systems.

For the purpose of insuring opening of the valves 7 and 4 at all pressures, their under faces are provided with vanes, fins or rudders indicated at 70 and 71 respectively, 130

of such design that they are caught by even a low pressure water flow and cause the valves to be swung into their full open positions.

5. In order to insure the water valve remaining in such position as to cause the vane 70 to be most effective, I mount a pin 72 in the top of said valve between the two branches of the lever 8, and to insure the proper assembly of the valve and lever I form on the 10 sides of the latter laterally projecting fins 73 which require the placing of the valve in such position that said pin is between the forks of the lever.
15. It is noted that the bolt 21 has a shoulder or collar adjacent its head designed to form a tight joint with the boss surrounding the opening in the casing through which it passes. With this arrangement there can be 20 no leakage around the bolt when the water valve is open even if the adjusting nuts 22 and 23 be removed.

I claim;—

1. The combination in a dry pipe valve of 25 a casing having a seat; a water valve co-operating with said seat; air controlled means including a lever for holding said valve closed; a member to which said lever is fulcrumed; and means for adjusting the 30 position of said member to vary the position of the valve relatively to its seat.
2. The combination in a dry pipe valve of 35 a casing having a valve seat; a water valve co-operating therewith; and air controlled means including a lever for normally holding said valve closed; a second lever mounted in the casing and serving as a fulcrum for the first lever; a threaded member connected to the second lever and extending 40 outside of the casing; with a nut on said threaded member for adjusting the position of said second lever.
3. The combination in a dry pipe valve of a casing having two external openings 45 respectively provided with valve seats; main air and water valves in the casing; an auxiliary air valve coacting with the seat of one of said openings of the casing; means connected with said auxiliary valve for holding the main water valve shut, said means including a lever fulcrumed outside of the casing, a weight movably mounted on said lever, a second lever in the casing and a link extending from the weight through 55 the second opening and operatively connected to the second lever; with a valve for closing said second opening.
4. The combination in a dry pipe valve of a casing; main air and water valves in 60 the casing; an auxiliary air valve normally closing an opening into the casing; a lever operative on said auxiliary air valve and fulcrumed on said auxiliary air valve; a weight fulcrumed outside of the casing and oper- 65 tive on said lever; with means connected to

said weight and operative on the main water valve to normally hold it closed.

5. The combination in a dry pipe valve of a casing having a main water valve and an air controlled valve; a lever fulcrumed outside of the casing upon said air controlled valve; a weight operative on said lever; and means for operatively connecting the weight and the main water valve to hold the latter closed. 75

6. The combination in a dry pipe valve of a casing having two openings in its external walls each provided with a valve seat; a water valve in the casing; an air valve for one of said seated openings; two levers mounted respectively on the inside and on the outside of the casing; a link connecting said levers and extending through the second of said openings; a valve carried by one of said levers for closing said latter opening; a weight pivoted to the second lever and operative on the air valve; and a tumbler on the first lever placed to engage the water valve to hold it shut. 80

7. The combination in a dry pipe valve 90 of a casing having two external openings each provided with a valve seat; a water valve in the casing; an air valve normally closing one of said openings; a weight outside of the casing normally acting to open 95 said air valve; an adjusting lever inside of the casing; a member extending outside of the casing and connected to said adjusting lever for swinging it on its pivot; a second lever fulcrumed to the first lever; a link connected to said second lever and operatively connected to the weight; means on the second lever for engaging the water valve to hold it shut; and a valve carried by said second lever for closing the second opening. 100

8. The combination in a dry pipe valve 105 of a casing having two external openings each provided with a valve seat; main water and air valves hinged within the casing; an auxiliary air valve hinged to swing on the same axis as that of the hinge of said main air valve and mounted to close one of the openings; two levers respectively mounted inside and outside of the casing; a link extending through the second of said openings and connecting said levers; a weight pivoted to the outer lever and operative upon the auxiliary air valve; a valve mounted upon the inner lever and placed to close the second of said openings; and means carried by said latter lever for engaging the water valve to hold it closed. 110

9. The combination in a dry pipe valve 115 of a casing having an inlet opening; a water valve hinged within the casing in position to close said opening; a lever hinged in the same line as the hinge of said valve; a member connected to said lever and extending outside of the casing; means on said member for adjusting the position of 120

130

the lever; a second lever in the casing fulcrumed to the first lever and having means for engaging the water valve to hold it shut; and an air controlled valve operatively connected to the second lever for holding it in a set position as long as the air pressure in the casing remains above a predetermined minimum.

10. The combination of a casing having an inlet and an outlet; two levers having their fulcrums in line; a valve for the inlet of the casing connected to one of said levers; a controlling valve connected to the other lever; means for operatively connecting said first valve-connected lever with the connection between the controlling valve and the other lever; with means for adjusting the latter lever to cause adjustment of the valve-connected lever and of the inlet valve relatively to its seat.

11. The combination of a structure having two valve seats; two valves respectively cooperating with said seats and mounted in positions to engage each other under predetermined conditions; with means for causing said valves to be locked together when they come into engagement.

12. The combination in a dry pipe valve of a casing having a water valve, and main and auxiliary air valves; means for automatically locking said air valves together when the main air valve opens; and mechanism connecting the auxiliary air valve with the water valve to hold the latter shut under normal conditions.

13. The combination of a structure having two valve seats; valves respectively cooperating with said seats; a lever mounted on one of said valves; and a projection on the other valve placed to coöperate with said lever to temporarily lock the valves together when one of them moves into engagement with the other.

14. The combination in a dry pipe valve of a casing having a water valve, and main and auxiliary air valves; a latch in the form of a lever on one of said air valves; a motion limiting web forming an inclosure on the other air valve and including a projecting part coöoperating with the lever to

lock said valves together when one of them moves to its open position, there being an opening in the web to give access to said lever; with mechanism connecting the auxiliary air valve and the water valve to hold the latter shut under normal conditions.

15. The combination in a dry pipe valve of a casing; air and water valves therefor; a lever hinged to the casing; means for movably connecting the lever and the water valve so as to permit of a limited independent movement of said valve; and means for connecting the lever and the air controlled valve to maintain the water valve in a closed position as long as the air pressure in the casing remains above a predetermined minimum, said means including a manually adjustable lever and an arm thereon detachably engaging the water valve.

16. The combination in a dry pipe valve of a casing having a main water valve; a transverse vane mounted on the under side of said valve in position to catch water flowing into the casing and accelerate the opening of said valve.

17. The combination in a dry pipe valve of a casing; a main water valve pivotally mounted therein; and a vane extending across the under face of said valve at a point relatively distant from the pivot thereof in position to receive water flowing into the casing and accelerate the opening of the valve.

18. The combination in a dry pipe valve of a casing; a lever fulcrumed therein; a water valve rotatably mounted on said lever; a vane on the face of said valve in position to receive water flowing into the casing to accelerate the opening of the valve; and means for limiting the possible angle through which the valve may rotate relatively to its lever.

In testimony whereof, I have signed my name to this specification, in the presence of two subscribing witnesses.

POWELL EVANS.
